UNITED STATES PATENT OFFICE.

EUGENE S. KILGORE, OF SAN FRANCISCO, CALIFORNIA.

ASH TRAY.

Application filed December 29, 1924. Serial No. 758,583.

My invention relates to tobacco-users' appliances, and particularly to an ash tray.

An object of my invention is the production of a readily accessible ash tray, which is so incorporated in the design and configuration of a standard such as a lamp standard that it is hardly distinguishable when not in use.

My invention possesses other objects and 10 features of advantage, some of which with the foregoing will be set forth in the following description of the preferred form of my invention which is illustrated in the drawings accompanying and forming part 15 of the specification. It is to be understood that I do not limit myself to the showing made by said drawings and description, as I may adopt variations of the preferred form within the scope of my invention as 20 set forth in the claims.

Referring to the drawings:

Figure 1 is a cross sectional view of the lid, showing a separate tray positioned therein to receive the ashes.

25 Figure 2 is a perspective view of my device, showing one of the lids in open position.

Figure 3 is a cross sectional view, the 30 plane of section being indicated by the line 3—3 of Figure 2.

In terms of broad inclusion my invention 35 comprises an open frame of such size and dimensions as will permit it to be incorporated into a standard such as a lamp standard, and over which any surface ornamentation appearing on the standard may be extended. The frame is interposed in the standard at a convenient height from the floor and is retained in position by suitable 40 members on the ends which are adapted to engage complementary members on the adjacent ends of the standard. A lid of generally clam shell shape forms a closure for the open side of the frame, and in horizontal 45 position becomes an ash tray. Means are provided for detachably mounting the lid, and preferably means are also provided for holding a supply of matches within the frame.

In detail my invention comprises an open 50 or ring-like frame 6, preferably a casting which may be made as a whole or in like halves adapted to be secured together. In Figure 2 of the drawing I have shown the frame composed of two like parts, but it is 55 obvious that such a device could readily

be formed by a single cored casting. A passage 7 is provided on each side of the frame so that any wires or tubes carried in the standard may be continued thru the frame. As a matter of design I prefer to 60 make the frame of oval or ellipsoidal shape, but this is of course, open to variations in accordance with the ideas of the designer. Any desired configuration and ornamentation 65 that is in harmony with the structure with which it is to be combined may be used.

Extending above the seats 8 at each end of the frame, are studs 9 adapted to engage in complementary sockets 11 in the adjacent ends of the standard. The point at which 70 the frame is interposed in the standard is such as to have the device at a height above the floor convenient for use when sitting.

Across the lower end of the frame, a bridge 12 is provided on which a block or 75 stud 13 may be formed to mount a match box. Demountably arranged on the bridge by any suitable means, is a lid 17 of generally clam shell shape, which normally closes the open side of the frame. Such a mounting preferably comprises the curved pins 14 set in the bridge and adapted to engage the studs 16 projecting inwardly from the edge of the lid. The arrangement of the parts is such that the lid is supported in either 80 the closed upright position or in the open horizontal position. When open the lid forms an ash tray and is securely held in this horizontal position by the bridge 12 which serves as a stop against which the 85 lower end of the lid contacts. In Figure 2 I have shown a cigar or cigarette rest 21 disposed at the upper end of the lid. Rests may also be provided on the sides of the lid if desired. 90

To insure against the accidental opening 95 of the lid, I provide a latch ring 22, which preferably surrounds the upper end of the frame adjacent the seat 8. This ring is preferably rotatably mounted and is formed 100 with slots 23 thru which the upper tip of the lid passes when the slot and lid are aligned.

The lid is normally closed, and to the 105 casual observer the device appears only as part of the general configuration and design of the structure in which it is interposed. I have shown the device as applied to a floor lamp standard, but it is obvious that it could be used in combination with any other suit- 110

able standard. When it is desired to use the ash tray, the latch ring is manipulated to release the lid which opens and lies in its horizontal position. A convenient supply of matches may be had by mounting a box of matches on the stud within the open frame. When the ashes are to be emptied the lid may be removed by raising the outer end slightly, then lifting the ash tray out of its mounting.

As shown in Fig. 1 a separate tray or pan may be incorporated in the lid, so that it is removable instead of demounting the lid. In this case the lid may be permanently pivoted to the frame.

I claim:

1. A device comprising an open frame, a bridge spaced from and extending across the bottom of the frame, and a lid comprising an ash tray demountably secured to said

bridge and adapted in one position to close the open side of the frame.

2. A device comprising an open frame, a bridge spaced from and extending across the bottom of the frame, a lid comprising an ash tray normally closing the open side of the frame, and hinge means demountably securing the lid to said bridge.

3. A device comprising an open frame, a bridge spaced from and extending across the bottom of the frame, a lid comprising an ash tray normally closing the open side of the frame, and hinge means demountably securing the lid to said bridge, the lower end of said lid abutting against the bridge to hold the lid in horizontal position.

In testimony whereof, I have hereunto set my hand.

EUGENE S. KILGORE.
